UNITED STATES PATENT OFFICE.

TONJES A. C. BOTH AND ALEXANDER H. TRUMBULL, OF STRATFORD, CONNECTICUT,
AND RALPH A. SCHOENBERG, OF NEW YORK, N. Y., (SAID SCHOENBERG NOW BY
JUDICIAL CHANGE OF NAME RALPH A. BELMONT,) ASSIGNEES TO THE CONNECTI-
CUT ELECTRIC MFG. CO., OF BRIDGEPORT, CONNECTICUT, A CORPORATION OF
CONNECTICUT.

FUSE-PLUG.

1,277,540.

Specification of Letters Patent. Patented Sept. 3, 1918.

Application filed January 19, 1915. Serial No. 3,178.

To all whom it may concern:

Be it known that we, TONJES A. C. BOTH and ALEXANDER H. TRUMBULL, both of Stratford, in the county of Fairfield and State of Connecticut, and RALPH A. SCHOENBERG, of New York, in the county and State of New York, have invented a new and useful Fuse-Plug, of which the following is a specification.

10 The main object of our invention is to increase the efficiency and safety of fuse plugs and especially those of the type having a screw shell body and non-brittle construction.

15 A feature of our invention is the provision of exterior insulation, preferably in the form of a band, applied to the shell body just above the threaded portion and in adjacency to the cover. This band is used so 20 that no live part of the shell of the plug will be exposed above the porcelain of the receptacle in which the plug is placed so that the hand of the operator will be protected and yet the plug can be used with receptacles of different depths.

25 Another feature of our invention is an arc-restrainer spaced from the wall of the shell and preferably this restraint is provided by an introverted or inwardly turned portion of the insulating non-brittle lining of the shell body. This arrangement also provides space for soldering the fuse to the shell which is an important advantage. We 30 preferably provide a passage in said lining, which passage may be an inclosed opening or a slot and in either case the fuse passes through the opening and across the lining so that any arc will be restrained on blowing the fuse.

40 Another feature is the use of means to prevent rotation of the center contact so that the fuse wire can not be twisted and in the preferred form we use an intermediate washer with pointed portions to engage an opening in the shell.

45 Another feature is the use of an intermediate member to keep the outer and inner washers spaced so that when the center contact is clenched a clear passage for gases 50 will be provided.

Another feature consists in making the

hand hold insulator and exterior insulator in one piece.

Another feature consists in making the insulating lining and inner washer in one 55 piece and preferably providing gas outlets at the bottom of the washer portion.

Other features will be pointed out below.

In the drawings:

Figure 1 is a central longitudinal sec- 60 tional view of a fuse plug embodying features of the invention;

Fig. 2 is a section on line 2—2 of Fig. 1;

Fig. 3 is a plan view of the fuse shown in Fig. 1 but with the hand-hold removed; 65

Figs. 4, 5, 6 and 7 are details hereinafter described;

Fig. 8 shows a receptacle with fuse in po- 70 sition therein;

Fig. 9 is an end view of a modified form of lining for the body;

Fig. 10 is a section on line 10—10 of Fig. 9;

Fig. 11 is an elevation showing a modifi- 75 cation; and

Fig. 12 is a modification hereinafter described.

Our improved fuse comprises a screw shell body member 1; a center contact 2 at the inner end of said shell, and a fuse 3 soldered 80 at one end to center contact 2 and at its opposite end to the shell 1. A peculiarity of our fuse is that the screw shell 1 forms the frame work or body of the structure on which all of the other parts are mounted 85 thus doing away with the usual porcelain body upon which it has heretofore been customary to mount the screw shell and other parts. The inner end of the screw shell 1 is made with an end wall 4 having 90 a rectangular opening 5 therethrough and also formed with radially disposed corrugations extending from near the periphery of the wall to the rectangular opening 5. Diagonally disposed within the rectangular 95 opening 5 is an intermediate washer 7. Upon the outside of washer 7 and end wall 4 is arranged an outer washer 8 formed with a central perforation through which the shank of center contact 2 extends. Upon 100 the inside of washer 7 is arranged an inner washer 10 formed with a central perfora-

tion 11 through which the shank of center contact 2 extends and with peripheral projections 12. The washer 10 occupies a position within the inner end of a tubular fiber 5 lining 13 provided within screw shell 1 and the projections 12 not only center washer 10 and contact 2 but they provide passageways 14 between them which communicate with the two spaces 15 at each side of washer 7. These 10 two spaces 15 are open through the corrugation 6 to the outside atmosphere. The outer side end of the screw shell 1 carries a disk of mica 16 which closes the outer end of the interior fuse chamber within lining 13 and shell 1, so that when the fuse blows out the 15 gases produced within the fuse chamber may escape in a staggered fashion through the ports 14, spaces 15 and corrugations 6. Thus the gases discharged from the fuse 20 plug when the fuse blows out are discharged from the plug at the inner end thereof into the receptacle shown at 17 in Fig. 8 thus minimizing fire hazard.

The center contact 2 is made with an exterior head or flange 18 and a shank 19 whose inner end is provided with a pair of tangs 20. After the shank 19 of center contact 2 is passed through washer 8, washer 7 and washer 10, the tangs 20 are bent down 30 or clenched onto washer 10 so as to cause said washer, washer 7 and washer 8 to be rigidly clamped between said tangs and flange 18 in such manner as to hold the washers against relative displacement the 35 intermediate washer spacing the other two washers for the passage of gas. At the same time the engagement of the ends of the washer 7 with the corners of the rectangular opening 5 serves to hold it and the other 40 two washers against rotative displacement with relation to the screw shell 1.

A feature of the invention consists in the employment of an introverted portion of lining 13 over, or through, which the fuse 45 3 extends, whereby any arc produced when the fuse blows out is restrained, that is, when the fuse blows out the spark will not extend from center contact 2 to shell 1 but will terminate or be extinguished by reason 50 of the presence of said introverted portion. The indentation or introversion provided in the lining 13 is shown at 21 in Fig. 3 and the outer edge of this indentation may be provided with a slot 22 within which the 55 fuse 3 extends and this indentation provides convenient space for attaching the fuse to the shell.

As usual the fuse 3 is soldered at its inner end to center contact 2 and at its outer end 60 to the screw shell 1.

The screw shell 1 is made at its outer end with an out-turned lip 23 inside of which is arranged a ring 24 of insulating material such as fiber and on top of this lip 23 is seated the mica disk 16, the margin of said

disk and the ring 24 being firmly clamped to the lip 23 and held against rotative displacement with relation thereto, by a metal ring 26 having an outer inturned lip 25 resting against the mica disk 16 and an inner in-turned lip 28 crimped around the ring 24. By grasping the ring 26 between the thumb and forefinger the fuse plug may be rotated to screw it into or out of its receptacle, the ring 26 and the mica disk serving as a cover 75 and also as a hand hold.

Another feature of the invention consists in providing the outer end of the screw shell 1 with an encircling collar or band 29 of insulating material confined between a head 80 30 on screw shell 1 and ring 24. In grasping the ring 26 to screw the plug into or out of its receptacle the thumb or forefinger would be liable to overlap ring 26 and contact with the exterior of screw shell 1 were 85 it not provided with the band 29 of insulating material adjacent to the hand hold and to ring 24. This band 29 may be of the diameter shown in Fig. 1, or the exterior diameter may be smaller as shown in Fig. 11. 90

In place of the two rings 24 and 29 we may employ a single ring 31, shown in Fig. 12 having an outwardly extending flange 24' and a downwardly extending flange 29'. This ring 31 can be substituted for the two 95 rings 24 and 29.

If desired the lining for the screw shell 1 may be made, as shown in Fig. 10, with an end wall 10' having a central opening 11' for the shank of center contact 2, and made 100 with marginal ports 14'. When this modified form of lining is used of course, its end wall 10' takes the place of the separate piece washer 10.

What we claim is:

1. A fuse plug comprising a shell body member; a center contact member; a fuse connecting said members; and an arc restraining lining for said body member to intercept the direct path of an arc from one 110 of said members to the other.

2. A fuse plug comprising a shell body member and an introverted arc-restraining lining within said body member; a center contact; and a fuse connecting the center 115 contact with the body member, the introverted portion intercepting the direct path from said center contact to the point of connection of the fuse and body member.

3. A fuse plug comprising a shell body 120 member; a cover with a transparent portion; a center contact insulated from said body member; a tubular insulating lining having an introverted portion; and a fuse leading from the center contact across said 125 introverted portion to said body member, said introverted portion intercepting the direct path from said center contact to the point of connection of the fuse and body member.

4. A fuse plug comprising a screw shell body member with a portion to engage a receptacle; an insulated vented chamber within said member; a fuse within said chamber; a hand hold; an exterior insulating band between the hand hold and engaging portion of the body member and of such a diameter as to enter said receptacle; and a center contact member at the entering end 10 of said plug, said center contact member being connected to the body member by the fuse.
5. A fuse plug comprising a shell body member having a portion threaded to engage a receptacle; a vented chamber within said body member; a hand hold; an exterior insulating band between the hand hold and the threaded portion and of such diameter as to enter said receptacle; and a center contact at the entering end of said plug.
6. A fuse plug comprising a screw shell body member; an insulating vented chamber within said body member; a hand hold; and a ring of material for insulating said hand hold from said body member to provide exterior insulation for a portion of said shell body member.
7. A fuse plug comprising a shell body member with a central opening; a center contact in said opening; means for insulating said contact from said member; and means engaging the wall of said central opening to prevent rotation of said contact with relation to said member.
8. A fuse plug comprising a shell body member with a central opening; a center contact in said opening and a plurality of washers insulating said contact from said member, one of said washers being rigidly connected to said contact and engaging the wall of said opening in said member to prevent rotation of said contact.
9. A fuse plug comprising a shell body member with a central opening; a center contact in said opening; material for insulating said contact from said member and having an extension engaging the wall of said opening to prevent rotation of said contact; and a gas outlet between said material and said wall.
10. A fuse plug of the screw plug type comprising a screw threaded shell; an insulating lining for said shell; a center contact secured to, and supported on, one end 55 of said shell; material insulating said shell and center contact; an outwardly extending flange near the opposite end of said shell; a ring of insulating material surrounding said shell and engaging one side of said flange; a pane of transparent insulating material closing one end of said shell and engaging the other side of said flange; and a metal ring surrounding said insulating ring for holding said pane in position, said metal ring being formed with a flange crimped
- around the insulating ring to clamp the latter to the flange of the shell and formed with a lip to engage said pane to clamp it to the flange of the shell; and an exterior insulating band around a portion of said shell.
11. A fuse plug comprising a shell body; an inner washer and an outer washer held by said body; a center contact clenched over said washers; and an intermediate washer 75 smaller than the inner and outer washers to space the inner and outer washers when the center contact is clenched and thereby to provide a gas outlet.
12. A fuse plug comprising a shell body 80 member; a center contact; a fuse connecting the center contact with the shell body member; and a non-brittle lining for said member having an introverted portion adjacent the point of connection of the fuse 85 and body member, said introverted portion intercepting the direct path from said center contact to said point of connection.
13. A fuse plug with a body member, a tubular lining; a center contact; a washer 90 at center contact end of said tubular lining, said washer having extensions for centering said washer with relation to the tube, the spaces between said extensions forming gas passages; means to keep a fixed relationship 95 of said washer with the body member; and means for securing the center contact position.
14. A fuse plug comprising a screw shell body member; interior insulation; a center 100 contact; a fuse; a metallic hand hold; exterior insulation for said body member; and a gas outlet from said body member.
15. A fuse plug comprising a shell body with a chamber; an insulating ring; a cover 105 for said chamber; means to clamp said ring and cover to said body; a center contact; a fuse in said chamber connecting the center contact with said body; and a band of exterior insulation for said body immediately 110 beneath said clamping means.
16. A fuse plug comprising a threaded shell body; a cover; a metallic ring clamping said cover to said body; and a band of insulation for said body exterior thereto and extending from said ring to the threaded portion of said body.
17. A fuse plug comprising a shell body member; a metallic hand hold; and a band 120 of insulation for said body member exterior thereto and in adjacency to said hand hold.
18. A fuse plug comprising a shell body member with a flange having a central opening; an inner washer ventilatively engaging one face of said flange; an outer washer engaging the other face of said flange; and an intermediate washer in said opening but having a portion spaced from the wall thereof to provide a gas outlet.
19. A fuse plug comprising a shell body 130

- 5 having a corrugated flange with a central opening; an insulating lining for said body; a washer spaced from said lining and engaging the inside of said flange; a second washer within, but having a portion spaced from the wall of said opening; and a center contact holding said washers in place, said corrugated portion and the spacing of the washers forming a staggered gas outlet.
- 10 20. A fuse plug comprising a screw shell; a chamber within said shell, a center contact at one end of said chamber; a washer having extensions for centering it with relation to said chamber, the spaces between said extension forming gas passages, said washer, except for said spaces, closing said end of said chamber; and means for securing the center contact in position.
- 15 21. A fuse plug comprising a shell body member; an insulated vented chamber within said body member; a fuse within said chamber; a center contact ventilatively attached to said body member at one end, and exterior insulation and a hand hold at the other end of said plug.
- 25 22. A fuse plug comprising a shell body; a center contact; an insulating lining with an end portion at the center contact end of said lining provided with gas passages, said portion keeping a fixed relation between the center contact and the body member.
